THERMOCOUPLE SUPPORT

James C. Woodson, Cleveland, Ohio, assignor to
 Lee Wilson Engineering Company, Cleveland,
 Ohio, a corporation of Ohio

Application August 16, 1938, Serial No. 225,124

4 Claims. (Cl. 136—4)

This invention relates to a support for a temperature responsive device such as is employed in various industries for checking temperatures and processes involving heating operations.

5 In many instances, particularly metallurgical processes, it is necessary to subject material to elevated temperatures, and it is desirable to check such temperatures accurately. It has been the practice heretofore to mount thermo-responsive 10 means such as thermocouples in furnaces, and it is the general object of this invention to improve upon such practice and mountings as have been employed heretofore. A particular object of the invention is to provide a support for mounting a thermo-responsive means in actual contact with the material being processed. In a preferred form the invention comprises a tubular member adapted to be inserted through a furnace wall and having thereon a resilient support for a sealing receptacle. A thermo-responsive element extends through the receptacle and the tube into contact with the material being treated.

The following detailed description refers to the accompanying drawing illustrating a present preferred embodiment. While the invention will be described and illustrated as applied to a furnace of the portable or cover type, an example of which is found in Wilson Patent No. 1,952,402, it will be understood that the invention may also be 20 installed on other types of furnaces as well. In the drawing

Figure 1 is a partial transverse section through a furnace of the cover type and the invention installed thereon;

25 Figure 2 is a partial sectional view showing a portion of Figure 1 to an enlarged scale.

Referring now in detail to the drawing, a furnace 10 comprises a base 11 and a cover 12. The base is composed of refractory brick 13 laid up on a bottom sheet 14 carried on structural members 15. The cover comprises refractory side walls 16 and walls 17, and the roof 18 built of suitable brick within a structural frame indicated generally at 19 for sheathing plates 20.

30 A charge support 21 is disposed on the base 11 and is adapted to receive a charge such as a coil of strip indicated at 22. A protective cover 23 overlies the coil and its support, the rolled edge of the cover 23 being seated in a sealing channel 24 extending peripherally of the support 21.

Radial tubes 25 are in spaced relation along the side walls of the cover and are provided with burners 26 extending into the lower end thereof. Fuel supplied to the burners through pipes 27 is burned in the tubes 25 with air induced into the lower

ends thereof, and the resulting combustion in the tubes heats them to radiant condition. The tubes 25 thus serve to heat the cover 23 and coil 22 by radiation and convection.

A tube 28 extends upwardly through the base 11 and may conveniently consist of upper and lower sections threaded into a coupling sleeve 29. The sleeve is welded to the bottom plate 14 of the base as at 30.

An annular plate 31 is welded to the lower section of the tube 28 intermediate its ends. Threaded guide bars 32 are spaced around the plate 31 and depend therefrom being secured thereto by nuts 33. Coil springs 34 are disposed on the rods 32 and rest on washers 35 supported 10 by nuts 36 threaded on the lower ends of the rods.

A sealing receptacle 37 surrounds the lower end of the tube 28, having an annular collar or flange 38 secured thereto and extending radially therefrom, resting on the springs 34. The collar 38 is 20 punched or slotted to receive the rods 32. The bottom of the receptacle 37 is formed by a plug 39 threaded thereto. The plug 39 carries a packing gland 40. A thermo-responsive member 41, which may conveniently be a tube enclosing 25 the hot junction of a thermocouple, extends through the gland 40, upwardly through the receptacle 37, and into and through the tube 28. The charge support 21 is provided with holes to admit the upper end of the member 41 to direct 30 contact with the coil 22 or other charge on the support 21. The nuts 36 are preferably adjusted initially so that the upper end of the member 41 extends slightly above the support 21 when the charge 22 is removed. When the charge is placed 35 on its support, the member 41 is forced downwardly and carries the receptacle 37 with it, thereby impressing the springs 34 slightly. The thermo-responsive member 41 is thus yieldably supported in engagement with the material being 40 processed.

The receptacle 37 is filled with sealing liquid such as oil indicated at 42, to a level below the lower end of the tube 28. The sealing liquid 42 prevents the loss of gas usually supplied to the 45 interior of the cover 23 to provide a non-oxidizing atmosphere for the charge during heating, and it also prevents the in-flow of air through the tube 28.

The advantages of the invention described 50 above will be recognized immediately. In the first place, the thermo-responsive member is maintained in direct contact with the material being heated at all times without any necessity for manipulation or adjustment by an operator. 55

At the same time the opening through which the thermo-responsive member extends into the furnace is sealed so that it is gas-tight. It will be apparent that more accurate temperature readings may be obtained when the thermo-responsive member is in accordance with the invention than when supported in other positions apart from the material being treated, as has been the practice heretofore. The invention thus contributes to the production of material of superior quality in cases where accurate control of temperature is important.

A further advantage is the ease with which the thermo-responsive member may be removed and replaced. For this purpose it is only necessary to unscrew the lower section of the tube 28 from the couple 29. The thermo-responsive member, the yielding support, and the sealing cup associated therewith may then be removed as a unit by withdrawing the member from the upper portion of the tube 28. Similarly, the thermo-responsive member may easily be removed from the sealing cup by releasing the packing gland 40. In addition to the foregoing advantages, the various parts making up the assembly for resiliently supporting the thermo-responsive member are simple and inexpensive to manufacture and require practically no maintenance in use.

While the invention has been illustrated as applied to a furnace of the cover type and particularly to the base thereof, it will be understood that it may also be installed in the side walls or roof of a furnace of any type. Other changes in the construction and arrangement disclosed

may, of course, be made without departing from the spirit of the invention or the scope of the appended claims.

I claim:

1. In a furnace, a tube extending thereinto from the exterior thereof, a liquid-filled receptacle outside the furnace into which said tube depends, thermo-responsive means mounted on said receptacle and extending through said receptacle and said tube and into the interior of said furnace, and means yieldably supporting said receptacle on said tube.

2. In a furnace, a tube extending thereinto from the exterior thereof, a liquid-filled sealing receptacle outside the furnace enclosing the exterior end of said tube, thermo-responsive means mounted on said receptacle and extending through said receptacle and tube, and means yieldably supporting receptacle on said tube.

3. In a furnace, a tube extending thereinto from the exterior thereof, a liquid-filled sealing receptacle outside the furnace enclosing the exterior end of the tube, a spring suspension on said tube for supporting said receptacle, and thermo-responsive means mounted on said receptacle and extending into the furnace through said receptacle and tube.

4. In a furnace, a tube extending thereinto from the exterior thereof, a liquid-filled sealing cup outside the furnace, said cup being movably carried on said tube and enclosing the exterior end thereof, and thermo-responsive means extending axially through said cup and tube and supported on said cup.

JAMES C. WOODSON. 35
